F. A. HENDRICKSON

LEVER ATTACHMENT

Filed May 8, 1922

UNITED STATES PATENT OFFICE.

FREDRICK A. HENDRICKSON, OF REVELSTOKE, BRITISH COLUMBIA, CANADA.

LEVER ATTACHMENT.

Application filed May 8, 1922. Serial No. 559,492.

To all whom it may concern:

Be it known that I, FREDRICK A. HENDRICKSON, citizen of Canada, residing at Revelstoke, in the Province of British Columbia and Dominion of Canada, have invented certain new and useful Improvements in a Lever Attachment; and I do hereby declare the following to be a full, clear, and exact description of the invention, 10 such as will enable others skilled in the art to which it appertains to make and use the same.

This invention provides for the manipulation of a lever by foot instead of the hand 15 and is of particular advantage in the operation of a railroad ditcher which usually has three control levers, one for the hoisting throttle, a second for the swinging throttle and a third for the boom engine throttle. 20 Changing from one lever to the other frequently results in confusion and delay which is obviated by the present invention since two of the levers are operable by hand and the third by foot, thereby enabling the machine to be operated faster and without confusion and resulting in more and better work in a given time.

Other objects and advantages will be apparent and suggest themselves as the nature 30 of the invention is understood.

While the drawing illustrates an embodiment of the invention it is to be understood that in adapting the same to meet different conditions and requirements, various changes 35 in the form, proportion and minor details of construction may be resorted to without departing from the nature of the invention.

Referring to the accompanying drawings forming a part of the specification,

40 Figure 1 is a front view of a lever provided with a foot operating attachment embodying the invention,

Figure 2 is a side view thereof,

Figure 3 is a top plan view, and

45 Figure 4 a detail.

Corresponding and like parts are referred to in the following description and designated in the several views of the drawings by like reference characters.

50 The numeral 1 designates the lever which

it is desired to be operated by foot and which ordinarily is manipulated by hand. In the present instance the lever 1 is designed to operate the boom engine. In accordance with this invention the lever 1 is 55 shortened and is provided at its upper end with a longitudinal slot 2.

The foot attachment comprises a rest 3 which is approximately of circular form and constructed of a length of round iron bent 60 into the shape substantially as shown. A plate 4 is welded or otherwise attached to a portion of the rest 3 and is formed with openings 5 to receive fastenings such as bolts whereby it is adjustably attached to the slotted end of the lever 1. Eye bolts 6 are attached to the rest 3 at opposite sides of the opening formed by omitting a portion thereof. The eyes or openings of the parts 6 are elongated vertically and receive a strap 70 7 which is adjustable by means of a buckle whereby to secure the foot when in position.

The rest 3 is adapted to receive the heel portion of the shoe worn by the operator and the strap 7 engages the heel portion of the shoe thereby preventing slipping of the foot and enabling the lever 1 to be positively operated in each direction for opening and closing the throttle as required. The rest 3 75 engages the front and sides of the heel 80 thereby preventing forward displacement of the foot whereas the strap 7 engages the rear of the heel and prevents rearward displacement of the foot.

Having thus described the invention, what 85 I claim is—

1. A lever attachment comprising a foot rest adapted to receive the heel of a shoe, spaced eye bolts projecting upwardly from the foot rest and having the eyes elongated 90 vertically and a heel strap engaging the elongated eyes of said bolts.

2. A foot attachment for levers comprising a rest of approximately circular form having a portion in the rear omitted, attaching elements at the ends of the rests bordering upon the openings formed by omitting a portion thereof and a heel strap connected to the rest by means of said 95 attaching element.

3. A foot attachment for levers comprising a rest of approximately circular form having a portion in the rear omitted, an attaching plate at one side of the rest, eye bolts applied to end portions of the rest adjacent the rear opening thereof, and a heel strap applied to the eye bolts.

In testimony whereof I affix my signature in presence of two witnesses.

FREDRICK A. HENDRICKSON.

Witnesses:

CAMILLO F. CASHATO,

MAUDE BROWN.
